UNITED STATES PATENT OFFICE.

HOWARD G. ALLEN, OF ALBION, NEW YORK.

SPRING-MOTOR.

1,351,727.

Specification of Letters Patent. Patented Sept. 7, 1920.

Application filed May 31, 1919. Serial No. 300,980.

To all whom it may concern:

Be it known that I, HOWARD G. ALLEN, a citizen of the United States, residing at Albion, in the county of Orleans and State of New York, have invented certain new and useful Improvements in Spring-Motors, of which the following is a specification.

The object of this invention is to provide a new and improved form of spring motor for use in toy vehicles and other mechanical toys.

This and other objects of this invention will be fully illustrated in the drawings, described in the specification and pointed out in the claims at the end thereof.

In the accompanying drawings,

Figure 1 is a perspective view of the toy vehicle in which the spring motor is used as a means for propelling it.

Fig. 2 is a detail perspective view of the governor mechanism for controlling the speed of the motor.

Fig. 3 is a partial side elevation and cross section of a modified series of spring units used for driving the motor.

Fig. 4 is a bottom plan view of the driving gear and ratchet mechanism of the motor.

Fig. 5 is a partial front elevation and sectional view of the motor, the motor being shown attached to the frame of the toy vehicle shown in Fig. 1.

Fig. 6 is a partial top plan view and horizontal section of the motor and support therefor.

In the several figures of the drawings, like reference numerals indicate like parts.

The motor as shown in the accompanying drawings is so constructed that it can be rigidly mounted on the stationary axle of the vehicle and supported thereby. The casing of the motor, in turn, is used to support the frame of the vehicle on the axle but is mounted to turn in the frame so that the axle with the motor may be set at any angle to the vehicle frame.

While but one form of toy vehicle (a truck) is shown in Fig. 1, it is apparent that the motor may be used for furnishing the necessary motive power for any other form of mechanical toy.

The motor comprises a series of spiral springs 1, 2 and 3 which are connected in series with one another. Each of these

springs is fastened with one end to a collar or sleeve and to a casing with the other end.

The series of springs shown in Fig. 5 are connected as follows:

The spring 1 is surrounded by the casing 4 to which the outer end of the spring is fastened at 5. The inner end of the spring 1 is fastened to the sleeve 6 at 7. The sleeve 6, in turn, is mounted to turn idly on the vertical power shaft 7^A. A flange 8 is provided on the sleeve 6 to which is riveted or otherwise suitably fastened the second casing 9 as shown at 10. In the second casing 9 is contained the spring 2 which is fastened thereto with its outer end at 11, while the inner end of the same spring is fastened to a second collar or sleeve 12 at 13, the sleeve 12 and casing 9 being mounted to rotate idly on the vertical shaft 7^A.

The sleeve 12 has a flange which is fastened to a third casing 16 at 17. This casing contains the spring 3 which is fastened thereto with its outer end at 18, the inner end of the spring 3 being fastened to the sleeve 19.

The sleeve 19 is keyed to the power shaft 7^A and rotates therewith. Keyed to the lower end of the shaft 7^A is the ratchet wheel 20. A bevel gear 21 is mounted to rotate idly on the hub of the ratchet wheel 20 and carries the ratchet pawl 22 which engages the ratchet teeth on the ratchet wheel 20. The spring 23, carried on the gear 21, is adapted to hold the pawl 22 in engagement with the ratchet teeth.

The bevel gear 21 meshes with the pinion 24 keyed to the driving shaft 25, on either end of which a driving wheel 26 is mounted. Also keyed to the shaft 25 is the gear 27, which gear is fastened to the side of the wheel 26 by means of suitable screws 28 which pass through the side of the gear 27 into the side of the wheel 26.

The train of gearing so far described is mounted on the stationary horizontal axle 29. This axle is bent at four points to form the three vertical members 30, 31 and 32 thereon in which suitable bearings are provided for the driving shaft 25 to rotate therein.

The casing 4 to which the spring 1 is fastened is slightly larger in diameter than the casings 9 and 16. The wall of the casing

4 extends down over the casings 9 and 16 to the stationary axle 29 to which the bottom of it is rigidly fastened. As heretofore described, the springs are connected in series, 5 the outer end of the spring 1 being held in place on the inside of the stationary casing 4, the inner end of this same spring being connected to the outer end of the spring 2 through the casing 9. The inner end of the 10 spring 2, in turn, is connected to the outer end of the spring 3 through the casing 16 and the spring 3 is fastened with the inner end thereof to the sleeve 19 keyed to the shaft 7^A.

15 On the rotation of the shaft 7^A by means of the winding key 33 the sleeve 19 rotates with it and begins to coil up the spring 3. The outer end of the spring 3 in turn rotates the casing 16 and coils the spring 2 around 20 the sleeve 12. The outer end of the spring 2 in turn rotates the casing 9 and with it the sleeve 6 until the spring 1 is wound up. In doing so, all of the springs 1, 2 and 3 are gradually wound up, the outer end of the 25 spring 1 being held stationary in the casing 4 until all of the springs are wound up and brought to the desired tension.

In turning the shaft 7^A the ratchet wheel 20 turns with it but is prevented from turning in the opposite direction during the winding up of the springs by the pawl 22. This pawl in turn is held from turning with the bevel gear 21 by holding the wheel 26 30 keyed to the shaft 25 to prevent its rotation.

35 In winding up the springs 1, 2 and 3 by means of the key 33, the first spring is connected with the shaft and thereafter each spring in its turn winds up until its tension overcomes the force necessary to wind up the 40 following spring until all of the springs are wound to the desired tension.

45 As soon as the springs are released they begin to unwind in succession. Spring 1 will unwind itself until its tension has decreased to a point where the tension of the spring 2 is greater after which spring 2 takes up the driving of the shaft and rotates it until its tension has decreased so that spring 50 can pick up the driving of the shaft and begin unwinding it. The springs unwind 55 successively in the foregoing manner until the last of the springs has been unwound.

60 In order to govern the speed of the motor and also adjust it to one of different speed, a governor is provided. This governor is mounted on the shaft 35 carried on the outer end of the upright member 30 on the axle 29. To the outer end of this shaft is fastened the pinion 36 which meshes with the gear 27 carried on the driving shaft 25. The inner end of the governor shaft 35 is mounted to rotate in a suitable bearing in the side of the stationary casing 4.

Pinned to the shaft 35 and mounted to

swing thereon are the arms 37 and 38, each 65 of which carries a weight or ball 39 on the outer end thereof. The arms 37 and 38 are angular in outline with the weights 39 at one end of the angle and the pivot pin 40 passing through near the middle of the legs 70 of the angle.

The apex of each of the angular arms 37 and 38 normally rests against the inner side of the dished disk 41. The tension of this spring may be increased or decreased by the 75 thumb nut 43 against which the outer end of the spring 42 rests. The thumb nut 43 is threaded on the shaft 35 and may be screwed in or out thereon. The dished disk 41 rotates with the governor arms 37 and 38 and 80 is adapted to project into the dished side of a second disk 44 which is held stationary on the vertical member 30. The operation of the governor is as follows:

On the rotation of the governor shaft 35 85 by the gear 27 the centrifugal force created thereby throws the governor balls 39 outwardly and, in doing so, forces the corner of the angular arms 37 and 38 against the disk 41 which in turn is forced thereby 90 against the stationary disk 44. The friction thus created between these disks operates to retard the rotation of the governor shaft 35 and in turn the speed of the whole motor.

95 By increasing or decreasing the pressure exerted by the spring 42 on the pivoted governor arms 37 and 38, which is done by screwing the thumb nut 43 in or out on the shaft 35, the speed necessary to create the centrifugal force for throwing out the governor weights may be varied. Thus when the tension of the spring is increased it takes a higher speed to make the weights 39 act so as to hold the rotating disk 41 against the stationary disk 44 and the motor in turn is 100 allowed to run correspondingly fast. The reverse is true when the tension of the spring is decreased, in which case the governor is more sensitive and operates to retard the speed of the motor.

105 In Fig. 3 is shown a modified form of connection between the springs 1, 2 and 3 in which but two casings are used. The casing 50 is held stationary on the shaft by the axle 29 while the casing 51 rotates within 110 this casing. Spring 1 has its outer end fastened to the outer wall 50 and its inner end to the sleeve 52. The sleeve 52 is made long enough to project into the casing 51 and has the inner end of the spring 2 fastened thereto. The outer end of the spring 2 in turn is fastened to the wall of the casing, which casing has also the outer end of the spring 3 fastened thereto. The inner end of the spring 3 is fastened to the collar 53 which 115 is keyed to the power shaft.

120 While the manner of fastening the springs to the casing is different in the construction

shown in Fig. 3, the operation remains the same as that described in connection with Fig. 5.

The motor is held in place on the frame 60 of the toy vehicle as follows:

The casing 4 is passed through a suitable opening in the frame 1, which frame comprises a horizontal board in this case. The bead 61 formed on the casing 4 is adapted to rest against the under side of the frame as shown in Fig. 5. An auxiliary casing 62 is then slipped over the casing 4 on top of the frame 60 and is held suitably in place on the frame 60. The lower edge of the auxiliary casing 62 and the bead 61 engage the edge of the opening in the frame and hold the motor in place therein.

The motor casing is normally prevented from turning in the frame 60 by the spring latch 63. This latch comprises a spring which is pivoted to the underside of the frame 60 with a pair of pins 64 and 65 fastened to the frame adapted to hold the latch in engagement with one of the grooves in the rack 66. The rack 66 is provided on the periphery of the casing 4 and the casing may be held at different angular positions in the frame by turning the motor casing until the spring latch 63 engages the desired groove in the rack 66 and holds the casing in place in that position.

As previously described, the motor and the driving wheel are mounted on the stationary axle and swing on the frame so that by turning the motor casing in the frame the wheels are shifted and are made to run in a direction corresponding to the angle in which the motor casing is held in the frame of the vehicle.

The driving wheels may be locked by means of a brake to prevent their rotation. This brake comprises the lever 70 which is pivoted on the shaft 25 and is mounted to swing along side the vertical member 30 of the stationary axle. The L-shaped arm 71, carried on the lever 70, is adapted to embrace a portion of the upright member 30 at a point near where the stationary disk 44 is held in place thereon. In swinging the lever toward the outer end of the upright

member 30 the outer end of the arm 71 is forced between the member 30 and the disk 44 and slightly shifts the disk 44 against the disk 41 and in so doing prevents the rotation of the governor, which in turn prevents the rotation of the whole motor.

I claim:

1. In a spring motor, the combination of a frame, a cylindrical housing mounted to rotate in said frame, a series of springs mounted in said housing, a power shaft driven by said springs, a stationary axle, said cylindrical housing being mounted on said stationary axle, a driving shaft mounted parallel to said stationary axle and carried thereby, and wheels mounted on said driving shaft, said driving shaft being geared to said power shaft and being driven thereby.

2. In a spring motor, the combination of a frame, a stationary axle, a cylindrical casing mounted on said axle and supporting said frame on said axle, a series of springs in said housing, a power shaft driven by said springs, a driving shaft mounted parallel to said axle, a train of gears mounted on said power shaft and said driving shaft, wheels carried on said driving shaft, and a governor driven by said driving shaft and operating to regulate the speed of said shaft.

3. In a spring motor, the combination of a stationary casing, a power shaft mounted to rotate in said stationary casing, a second casing mounted to rotate on said power shaft within said stationary casing, a coil spring connecting said shaft with said second casing, a second coil spring connecting said second casing with said first casing, means to hold said shaft from turning in one direction on the manual turning of said power shaft, a driving shaft, a pinion mounted on said driving shaft, a bevel gear mounted on said power shaft, said bevel gear being adapted to mesh with said pinion on said driving shaft, a governor driven by said driving shaft, and wheels mounted on each end of said driving shaft.

In testimony whereof I affix my signature.

HOWARD G. ALLEN.
